(57) **CLAIM**

The ornamental design for a support bracket for modular furniture as shown and described.

DESCRIPTION

FIG. 1 is a top view of a support bracket for modular furniture;

FIG. 2 is a bottom view of the support bracket for modular furniture of FIG. 1;

FIG. 3 is a front view of the support bracket for modular furniture of FIG. 1;

FIG. 4 is a rear view of the support bracket for modular furniture of FIG. 1;

FIG. 5 is a left-side view of the support bracket for modular furniture of FIG. 1;

FIG. 6 is a right-side view of the support bracket for modular furniture of FIG. 1;

FIG. 7 is a front perspective view from a left-side of the support bracket for modular furniture of FIG. 1;

FIG. 8 is a rear perspective view from a left-side of the support bracket for modular furniture of FIG. 1;

FIG. 9 is a front perspective view from a right-side of the support bracket for modular furniture of FIG. 1;

FIG. 10 is a rear perspective view from a right-side of the support bracket for modular furniture of FIG. 1;

FIG. 11 is a perspective view from a left-side of the support bracket for modular furniture of FIG. 1 used for forming an item of modular furniture;

FIG. 12 is a perspective view from a right-side of the support bracket for modular furniture of FIG. 1 used for forming an item of modular furniture;

FIG. 13 is an exploded view of the support bracket for modular furniture of FIG. 1 used for forming an item of modular furniture;

FIG. 14 is a top view of a first variant of a support bracket for modular furniture;

FIG. 15 is a bottom view of the support bracket for modular furniture of FIG. 14;

(Continued)

FIG. 16 is a front view of the support bracket for modular furniture of FIG. 14;
 FIG. 17 is a rear view of the support bracket for modular furniture of FIG. 14;
 FIG. 18 is a left-side view of the support bracket for modular furniture of FIG. 14;
 FIG. 19 is a right-side view of the support bracket for modular furniture of FIG. 14;
 FIG. 20 is a front perspective view from a left-side of the support bracket for modular furniture of FIG. 14;
 FIG. 21 is a rear perspective view from a left-side of the support bracket for modular furniture of FIG. 14;
 FIG. 22 is a front perspective view from a right-side of the support bracket for modular furniture of FIG. 14;
 FIG. 23 is a rear perspective view from a right-side of the support bracket for modular furniture of FIG. 14;
 FIG. 24 is a perspective view from a left-side of the support bracket for modular furniture of FIG. 1 used for forming an item of modular furniture;
 FIG. 25 is a perspective view from a right-side of the support bracket for modular furniture of FIG. 1 used for forming an item of modular furniture; and,
 FIG. 26 is an exploded view of the support bracket for modular furniture of FIG. 14 used for forming an item of modular furniture.
 The portions of the drawings shown in broken lines do not form part of the design.
